UNITED STATES PATENT OFFICE.

HENRY C. LAMPE, OF ST. LOUIS, MISSOURI.

DESIGN FOR A MONUMENT.

Application filed March 28, 1929. Serial No. 30,656. Term of patent 14 years.

To all whom it may concern:

Be it known that I, HENRY C. LAMPE, a citizen of the United States, residing at the city of St. Louis, in the State of Missouri, have invented a new, original, and ornamental Design for a Monument, of which the following is a specification, reference being had therein to the accompanying drawing, forming part thereof.

I claim:

The ornamental design for a monument as shown.

In testimony whereof, I hereunto affix my signature.

HENRY C. LAMPE.
